UNITED STATES PATENT OFFICE.

WILLIAM E. PEDRICK, OF BUFFALO, NEW YORK, ASSIGNOR TO LARKIN CO., OF BUFFALO, NEW YORK.

MECHANISM FOR FEEDING STENCILS OR ANALOGOUS ARTICLES.

Application filed May 3, 1921. Serial No. 466,500.

To all whom it may concern:

Be it known that I, WILLIAM E. PEDRICK, a citizen of the United States, residing at Buffalo, in the county of Erie and State of New York, have invented a new and useful Improvement in Mechanism for Feeding Stencils or Analogous Articles, of which the following is a specification.

This invention relates to mechanisms for feeding sheets or similar articles, and more particularly to mechanisms for feeding stencils in connection with addressing machines or the like.

In addressing machines as heretofore made, the stencils are arranged in suitable frames or individual holders or containers which protect the stencils from injury which might be caused by the parts of the machine and by contact of the stencils with each other, and which cooperate with parts of the machine to effect the feeding of the frames and stencils to a printing or inking mechanism. Consequently when a large number of stencils is used, a large amount of space is occupied by the stencil frames and also considerable time is required to place the stencils into the frames.

One of the objects of this invention is to provide a feed mechanism for feeding stencils which is capable of handling the stencils without the usual stencil frames.

Other objects of this invention are to provide a mechanism of this kind which is so constructed that the individual stencils may be removed from the stack without rubbing the stencils against each other; also to provide means of improved construction for feeding the stencils from the stack to the printing mechanism; also to provide improved means for depositing the stencils in a magazine or stack after the same have passed through the machine; also to improve the construction of machines of this kind in other respects hereinafter specified.

In the accompanying drawings:

Fig. 1 is a longitudinal sectional elevation of a stencil feeding mechanism embodying the invention, showing the same applied to a well known type of addressing machine, the section being on line 1—1, Fig. 2.

Fig. 2 is a top plan view of the stencil feeding mechanism.

Figs. 3 and 4 are fragmentary top plan views thereof, partly in section, showing

parts of the stencil feeding mechanism in different positions.

Fig. 5 is a fragmentary longitudinal sectional elevation thereof on line 5—5, Fig. 3, on an enlarged scale.

Fig. 6 is a fragmentary transverse sectional elevation thereof on line 6—6, Fig. 3, on an enlarged scale.

Fig. 7 is a fragmentary transverse section on line 7—7, Fig. 4.

Fig. 8 is a fragmentary end elevation thereof.

Fig. 9 is a fragmentary longitudinal sectional elevation thereof on line 9—9, Fig. 8.

Fig. 10 is a fragmentary sectional plan view thereof on line 10—10, Fig. 8.

Fig. 11 is a detached view of the stencil holding finger and the actuating cam therefor.

Figs. 12 and 13 are fragmentary longitudinal sections of the stencil feeding mechanism on an enlarged scale, showing some of the parts in different positions.

Figs. 14 and 15 are fragmentary longitudinal sectional elevations on line 14—14 Fig. 4, showing the parts in positions different from those shown in Fig. 4.

Fig. 16 is a diagrammatic plan view showing the operation of the mechanism for removing the stencils from the bottom of the stack.

Fig. 17 is a perspective view showing the under side of one of the stencil engaging spring members.

Fig. 18 is a perspective view of one of the stencils.

Fig. 19 is a transverse sectional elevation of the stencil feeding mechanism on line 19—19, Fig. 2.

Fig. 20 is a fragmentary top plan view of the stencil discharge portion of the mechanism.

Figs. 21 and 22 are fragmentary longitudinal sectional elevations thereof showing some of the parts in different positions.

Fig. 23 is a fragmentary transverse section thereof on line 23—23, Fig. 20.

The stencil feeding mechanism forming the subject matter of this invention may be applied to any desired printing or addressing machine, and is shown in the drawings as forming a part of an addressing machine of well known type. This addressing machine has a frame including a substantially

horizontal frame member A, and a pair of upright frame members A' which support a table B. The frame members A' are provided with bearings for a drive shaft C which receives power from a gear C'. The machine includes a feeding mechanism (not shown) for the articles to be addressed, and an ink-applying mechanism of which only an ink-applying roller D is shown in Fig. 1. 5 The addressing machine shown also includes a movable platen E actuated by suitable mechanism mounted on the drive shaft C. All of these parts may be of any suitable or usual construction, and of themselves constitute 10 no part of this invention.

X represents the stencils which may be of any usual or suitable type and which are generally made of paper or other relatively thin material and which are perforated in 15 the usual manner to permit the ink from the ink-applying roller D to pass through the perforations to the articles to be addressed or printed. Since these perforations are irregular in form and may form projecting 20 parts on the stencils which may engage the perforated portions or projections of an adjacent stencil, it has been heretofore considered desirable to confine each stencil in an individual frame or holder and thus keep 25 the stencils out of engagement with each other.

By means of my stencil feeding mechanism, the stencils can be fed from a stack of stencils in which the stencils lie face to 30 face, since the parts of my feeding mechanism are so constructed that the stencils are separated from the stack in such a manner that the perforated portions of one stencil will not engage or interlock with the perforated portion of another stencil. This is 35 accomplished by moving each stencil away from an adjacent stencil in a direction substantially perpendicular to the face of the stencil, thus avoiding the sliding or rubbing 40 of a stencil while in contact with another stencil. After the stencil has been completely separated from an adjacent stencil, the stencil may be moved in any desired direction.

50 In the embodiment of the invention shown in the drawings, the stencils to be fed are arranged in a magazine or substantially vertical guideway formed by upright stencil guide members 25, 26 and 27, the lower ends 55 of which are secured to a table or plate 28 secured to the table B of the machine. This plate 28, in the construction shown, is formed integral with a frame member 29 on which many of the parts of the stencil feeding 60 mechanism are mounted. The stencils, in the construction shown, are removed from the bottom of the magazine and this is accomplished by first completely separating the lowest or bottom stencil from the other 65 stencils of the stack in the magazine.

In the mechanism shown in the drawings, the first step in separating the lowermost stencil from the other stencils of the stack consists in drawing one edge of the lowermost stencil downwardly away from the next 70 stencil. In the particular construction shown for this purpose, this is accomplished by means of a suction device or cup 30 which is preferably made of flexible material such as rubber, and is arranged at the upper end 75 of a suction pipe 31. The lower end of the suction pipe is connected preferably by means of a flexible tube 32 with a suction cylinder 33 supported on the frame 29 and having a piston 34 arranged therein. The cylinder 33 80 is also provided with an opening 35 adapted to be closed by a suitable valve 36 when it is desired to create in the cylinder a partial vacuum or suction, and which may be opened to the atmosphere when it is desired to break 85 the partial vacuum or suction in the cylinder. The piston 34 may be reciprocated by any suitable means, being connected in the construction shown by means of a connecting rod 37 with a crank 38 secured on the 90 drive shaft C. Any other means for producing the necessary suction may be provided.

In order to move the suction device upwardly into engagement with the lowermost stencil and to move the same downwardly 95 for withdrawing a part of the stencil from engagement with an adjacent stencil, the following mechanism is preferably employed.

The suction tube 31 is secured to a guide member 40 slidably mounted in brackets 41 100 and 42 arranged on the frame member 29, Fig. 9, the guide member 40 being provided with an offset portion 43 to which the suction tube is secured by means of nuts 44 or the like. This guide member insures a vertical movement of the suction member so that that part of the stencil engaged thereby will be moved away from the adjacent stencil substantially in a direction perpendicular to the faces of these stencils. The reciprocation of the guide member and suction device is, in the construction shown, accomplished by means of a bell crank lever pivoted at 46 and having an arm 47, the end of which engages in a bifurcated portion 48 of the guide 110 member 40. Another arm 49 of the bell crank lever is provided adjacent to its end with an antifriction roller 50 which is held in engagement with a cam 51, by any suitable means, such for example as by a spring 52. The cam 51 is secured on an upright shaft 53 and the face of the cam 51 which engages the roller 50 is so formed as to produce the desired movement of the bell crank lever and the suction device.

The opening and closing of the passage 35 in the cylinder 33 is preferably controlled by means of a cam 55 arranged on a second upright shaft 56 and engaging a roller 57 secured on a lever 58 pivoted on a bracket 59, 130

as shown in Fig. 10. The valve 36 is connected to the lever 58, and a spring 60 normally presses the lever in a direction to press the valve 36 over the opening 35 for closing the same. The cam 51 controlling the movement of the suction device, the cam 55 controlling the suction break valve 36 and the crank 38 are so proportioned and arranged relatively to each other that when the suction device engages with the lowest stencil 5 a partial vacuum is created in the cylinder 33 which is transmitted to the suction device. The suction device is then moved downwardly carrying the front edge of the stencil 15 with it and after an interval of time the suction is broken so that the stencil is released from the suction device as shown in Fig. 12.

After an edge of the lowermost stencil has 20 been drawn downwardly, the complete separation of the lowermost stencil from the stack is effected. This is accomplished in the construction shown by means of a pair of rotary disks 65 and 66 which are mounted 25 respectively at the upper ends of the vertical shafts 53 and 56 and which revolve in opposite directions as indicated by the arrows in Figs. 3 and 4. These shafts are suitably journaled in the frame member 29 and may 30 be driven from the drive shaft C in any desired manner, for example, by means of a gear 68 mounted on the drive shaft C and meshing with gears 69 and 70 secured on the shafts 53 and 56. The disks 65 and 66 are 35 arranged adjacent to each other in such a manner that the stack of stencils is supported by and rests upon the disks. Each of the disks is provided with a recess 72 extending inwardly from the peripheral portion of the disk, and at one side of the recess each disk 40 is provided with a projecting lip or part 73. The rotation of the disks is so timed relatively to the movement of the suction device that the lips 73 of the disks will pass between 45 the lowermost stencil and the other stencils of the stack from opposite sides of the stencil, after the front edge of the lowest stencil has been drawn downwardly by the suction device. The further rotation of the disks 50 causes the lips 73 to effect a separation of the entire stencil from the other stencils of the stack by causing parts of the lowest stencil to pass through the slots 72 during the rotation of the disks. This causes the lowest 55 stencil to be separated from the adjacent stencil without movement of this stencil relatively to the adjacent stencil in a direction to cause interlocking or catching of the perforated portions of the stencils and also ensures a positive and complete separation of 60 the two stencils, even if the ink on the stencils tends to cause them to stick together. The suction device acts on the end portions of the stencils which are not coated with ink, 65 while the positively acting disks are relied

upon to separate those parts of the stencils which might tend to adhere to each other. When the disks are in the positions shown in Figs. 2 and 4, the lowermost stencil is below the disks and the other stencils of the 70 stack rest upon the upper faces of the disks. After suction in the suction device is broken, the lowermost stencil is ready to be removed from its position beneath the stack of stencils. 75

In case it is found desirable not to depend solely upon the suction device to hold the lowermost stencil against lengthwise movement while passing through the slots 72 in the disks, an additional holding device for 80 the stencil may be provided. This holding device, in the construction shown, includes a holding finger 75 secured to the upper end of a lever 76 pivoted at 77 in the frame member 29. The lower end of this lever is 85 preferably provided with a roller 79 engaging the upper face of a cam 80, also mounted upon the upright shaft 53. In order to hold the roller in engagement with the face of the cam 80, a spring 81 is preferably employed. 90 The face of this cam is so formed that after the suction device has pulled downwardly the front edge of the lowermost stencil, the holding finger 75 will move downwardly in an arc of a circle from the position shown in 95 Fig. 13 to the position shown in Fig. 12, and press a part of the front edge of the stencil against the plate or table 28. The holding finger will thus prevent rearward movement 100 of the stencil due to the friction between the stencil and the separating disks 65 and 66, and the cam again raises the holding finger 75 out of engagement with the stencil when the stencil is ready to be moved forwardly 105 from its position underneath the stack. Any 105 other means for positively holding the stencil against rearward movement may be provided, or, if desired, these holding means may be omitted.

In order to move the stencils to the 110 printing mechanism after they have been separated from the stack and after they are positioned beneath the stack-supporting disks 65 and 66 upon the plate 28, the following construction is preferably employed: 115

The table 28 has a longitudinal groove 87 extending underneath the stack of stencils and into which the lowermost stencil is discharged after the same has passed beneath the stack-supporting disks 65 and 66. The 120 forward movement of the stencil is effected, in the construction shown, in a step by step motion by means of a reciprocating sliding bar 90. This bar is provided with an enlarged portion or plate 91 which is adapted to pass over the lowermost stencil and is provided at its rear end with a suitable stencil-engaging device which may be in the form of a spring member 92 secured to the plate 91 and held in place by means of a protect- 125 130

ing or covering plate 93 which limits the forward movement of the spring. This spring is provided at its outer end with a stencil-engaging hook 94 which is yieldingly pressed downwardly by the spring and is adapted to engage the rear end of the stencil when the plate is in a position underneath the stack of stencils, as shown in Fig. 4. The reciprocating bar 90 is provided on its inner face with a longitudinal slot or recess into which the edges of the stencils are adapted to enter. The upper flange bounding this slot is omitted at the outer end portion 95 of the reciprocating bar 90 and this end portion 95 is arranged in position to receive one edge of the stencil as the same is moved downwardly by the disks 65 and 66. The movement of the reciprocating bar from the position shown in Fig. 20 to the position shown in Fig. 4 causes the edge of the stencil to enter into the slot in the sliding bar at the same time that the plate 91 passes over the stencil, and at the end of this movement the hook 94 of the 25 spring member 92 engages the rear edge of the stencil, as shown in Fig. 12. The stencil is prevented from moving rearwardly during this movement of the reciprocating bar by means of the stencil guide member 25 by 30 the suction device, and by the finger 75, if the same is used. When the hook 94 reaches the stencil-engaging position the suction is broken in the suction device and the finger 75 is lifted, so that when the sliding bar 35 moves from the position shown in Fig. 4 to the position shown in Fig. 3, the stencil-engaging hook 94 draws the stencil from the position underneath the stack into the position indicated by X'. The stencils may be 40 advanced from the position X' by any suitable means. In the construction shown in the drawings, the reciprocating bar is provided with a plurality of stencil-engaging springs 97 arranged at intervals on the bar 45 and provided on their lower faces with stencil-engaging hooks 98, as shown in detail in Fig. 17. Each of these stencil-engaging springs is secured on an arm or bracket 99 having, in the construction shown, a slot 100 through which a screw or other holding means 101 passes for securing the springs to the reciprocating bar. These springs are 50 preferably made of very light material so that the stencil-engaging hooks 98 pass over the faces of the stencils with very little resistance.

In order to prevent the hooks from moving the stencils rearwardly, a stationary stencil-holding bar 105 is preferably provided which is arranged to engage the opposite sides of the stencils and is also provided at its inner side with a longitudinal slot or recess into which the side edges of the stencils enter. The stationary bar 105 is 60 provided with spring stencil-engaging mem-

bers 106 substantially similar in construction to the spring member 97 of the reciprocating bar. As the stencil is moved by the reciprocating bar from its position underneath the stack, an edge of the stencil enters into 70 the slot in the stationary bar 105. The stationary bar 105 and the reciprocating bar 90 are spaced apart so that only the opposite edges of the stencils are supported, thus leaving the intermediate portions thereof 75 free to be acted upon by the printing or inking mechanism.

In the operation of this portion of the mechanism, the stencils are fed by the reciprocating bar into positions in which the 80 spring stencil-retaining members 106 of the stationary bar engage the rear edges of the stencils, whereupon the reciprocating bar moves rearwardly so that each spring member 97 thereof moves into engagement with 85 the rear end of the next stencil. The stencils are thus successively moved from the position underneath the stack to the positions X', X², X³, X⁴, and in the position X⁴, in the construction shown, the inking or printing operation is effected.

The reciprocating bar 90 may be guided on the table B and plate 28 in any desired manner, the bar, in the construction shown, being arranged in a recess in the plate 28 and 95 confined therein by means of a retaining plate 110, and the opposite end of the bar is guided in its movement by means of a retaining guide plate 111 secured to the table B, Figs. 2 and 20. The mechanism for reciprocating the bar 90 may be of any suitable or usual construction, that shown including a depending arm 112 secured on the reciprocating bar and connected by means of a link 114 to a lever 115 pivoted at 116 on 100 the frame member A of the machine. The lever is preferably provided with a roller 117, Fig. 1, engaging in a slot 118 of a cam 119 secured on the main drive shaft C, the cam being so formed as to oscillate the lever 115 and thus give the reciprocating slide the 110 desired amount of movement.

After the printing operation is completed, the stencils are successively moved by the reciprocating bar 90 to positions X⁵ and 115 X⁶ and are then discharged by the reciprocating bar into a stencil-discharge magazine 125, which may be of any suitable construction, that shown consisting of a plurality of upright members 126 adapted to engage the edges of the stencils. The magazine is also provided with means for supporting the stack of stencils, such for example as a cage 120 slidably arranged in the magazine. This cage consists of upper and lower plates or 125 guide members 127 and 128 which slidably engage the upright members 126. The cage is supported by a spring 130 suitably secured at its upper end on a stationary part of the frame of the machine and having its lower 130

end secured to the cage so that the spring permits the cage to be moved downwardly in the magazine by the weight of the stencils. Consequently adjustment of the stencil-supporting cage is not necessary.

The means for discharging the stencils from the reciprocating bar 90 into the stencil-receiving magazine may be of any usual or suitable construction, those shown including a cover 133 removably arranged over the top of the discharge magazine. In the construction shown, this cover has an arm 134 which is pivoted at 135 on a stationary part of the machine. The cover 15 may be swung about the pivot 135, as indicated in Fig. 2, and an arm or handle 136 may be used for swinging the cover so as to render the discharge magazine accessible for removing the stencils accumulated there- 20 in.

The cover 133 of the discharge magazine is provided with means for engaging the stencils carried to the top of the magazine by the reciprocating bar 90. For this purpose the cover is provided in the construction shown, with a pair of spring members 138 having detents 139, Figs. 21 and 22, which engage the rear end of the stencil and prevent the same from being moved backwardly by the slide 90.

The stationary channeled guide bar 105 terminates at the stencil-receiving magazine and consequently when the reciprocating bar 90 is moved to the limit of its position 35 over the magazine, the stencil will be engaged at one edge only. In order to prevent this engagement of the stencil by the reciprocating bar from drawing the stencil by friction out of alinement, a stencil-holding clip or arm 143 is preferably provided 40 which is adapted to engage a corner of the stencil in such a way as to prevent the turning of the stencil, due to the return movement of the reciprocating bar. By means of 45 the arrangement specified, the stencils are all kept in correct alinement with each other so that they can be readily removed from the magazine and again used in an addressing machine.

50 The machine is also preferably, although not necessarily, provided with an alarm device which is adapted to sound a warning in case the feeding mechanism fails to withdraw a stencil from the magazine at each 55 operation of the machine. In the construction shown for this purpose, the plate 91 of the reciprocating bar 90 is provided with a hole or aperture 145 through which an electric contact pin 146 suitably connected in an 60 electric circuit (not shown) and mounted on an arm 147, may pass while the plate is temporarily at rest in its forward position. The arm 147 may be moved by any suitable means (not shown), and when a stencil is 65 beneath the plate 91, the stencil will act as

an insulator to prevent the completing of a circuit from the contact pin 146 to the plate 28 underneath. When a stencil is missing underneath the plate 90, the pin 146 will contact with the plate 28 and thus complete 70 an electric circuit, by means of which any suitable alarm device (not shown) may be actuated. Any other device for this purpose may, however, be used, if desired. The plate 91 is preferably also provided with an open 75 portion 150 through which a defective stencil may be removed from underneath this plate.

In the operation of the machine, the lowermost stencil of the stack is first engaged by the suction device which pulls the front edge of the lowermost stencil downwardly. The lips 73 of the revolving disks then pass between the lowermost stencil and the remaining stencils of the stack and the 85 rotation of the disks causes a complete separation of the lowermost stencil, permitting the stencil to drop into a position beneath the disks. If desired, the stencil may be held against rearward movement while engaged by the disk by means of the holding finger 75, in addition to the suction device. After the stencil has passed beneath the disks, the reciprocating bar 90 moves rearwardly, causing the stencil to enter into the 95 longitudinal slot in the side of this bar. When the bar has reached the limit of its movement, as shown in Fig. 4, the stencil-engaging spring member 92 thereof engages the rear edge of the stencil and the suction 100 device is then broken. When the reciprocating bar moves in the opposite direction the stencil is withdrawn from its position underneath the stack and moved into the guide slot in the stationary guide 105 bar 105. When the reciprocating bar has reached the limit of its movement in this direction, as shown in Figs. 2, 3 and 13, the holding fingers of the stationary bar engage the rear edge of the stencil and prevent the 110 rearward movement thereof. The suction device then engages the next stencil and the operation is repeated. At each forward movement of the reciprocating bar the stencils are advanced to the extent of one stroke 115 and when the stencils reach the position X⁴ the inking or printing operation is effected, the reciprocating bar remaining stationary for a sufficient interval of time to permit the printing to take place and 120 also to permit the suction device and disks to separate another stencil from the bottom of the stack. The stencils are finally discharged by the reciprocating bar into the discharge magazine 125, from which they 125 may be removed from the machine.

The machine described has the advantage of being able to handle stencils, which must necessarily be made of relatively thin material, without necessitating the use of 130

frames into which the stencils are inserted. This effects a very considerable saving, in the first place, of the cost of the frames themselves, and in the second place, of the amount 5 of storage space required for the stencils. The machine described is more efficient to operate than machines in which the stencils are arranged in holders since a greater number of stencils may be placed in the magazine 10 at one time. The machine described has the advantage of separating adjacent stencils without rubbing the surfaces of the stencils relatively to each other, this being accomplished by withdrawing a stencil from 15 an adjacent stencil in a direction substantially at right angles to the surfaces of the stencils. It is also desirable to separate a stencil from an adjacent stencil by successively separating different portions thereof, 20 this being accomplished in the construction described, by first separating an end of the stencil and then by having the lips separate the remaining portions by a gradual movement in the general direction of the length 25 of the stencils. The machine described also has the advantage of operating mainly on the edge portions of the stencil, thus avoiding injury to the perforated portions thereof and avoiding the rubbing of ink from the 30 perforated portion to other portions of the stencils, the middle or perforated portions being separated from an adjacent stencil due to the fact that the disks enter between the two stencils. The machine described is 35 rapid and efficient in its operation and simple and economical in construction.

While the machine embodying the invention has been described as adapted particularly for feeding stencils in connection with 40 an addressing machine, yet it will be understood that it is not intended to limit the feeding mechanism to this use, since the mechanism shown may be used equally well in connection with the feeding of sheets or other 45 flat articles. In those claims not particularly limited to stencils, it is understood that the mechanism recited may be used for feeding sheets or analogous articles other than stencils.

50 I claim as my invention:

1. In an addressing machine, a mechanism for feeding stencils to an inking mechanism, including a stencil magazine in which the stencils are arranged in contact with each 55 other, means at one end of said magazine for moving a stencil in a direction substantially perpendicular to the face of the stencil completely out of engagement with the adjacent stencil, and a stencil - advancing 60 mechanism for moving the stencil out of alignment with said magazine to said inking mechanism.

2. In a stencil feeding mechanism, the combination of a magazine in which the 65 stencils are arranged with their flat faces in

contact, mechanism engaging the edge portions of the stencils for removing a stencil from the magazine in a direction substantially perpendicular to the face of the stencil, so that the entire stencil is out of contact 70 with an adjacent stencil, and means for moving the stencil in another direction away from said magazine after the stencil has been moved out of contact with an adjacent stencil.

3. In a stencil feeding mechanism, the combination of a magazine in which the stencils are arranged with their flat faces in contact, mechanism acting on one stencil at a time for removing a stencil from the 80 magazine, said mechanism acting successively on different portions of the stencil and drawing the entire stencil out of engagement with an adjacent stencil substantially in a direction at right angles to the face of 85 the stencils, and means for moving the stencils in another direction away from said magazine.

4. In a stencil feeding mechanism, the combination of a magazine in which the 90 stencils are arranged with their flat faces in contact, said stencils having perforated middle portions and imperforate edge portions, means acting on one end of a stencil for separating said end from an adjacent 95 stencil, and means engaging the side portions and entering between the stencil to be removed and an adjacent stencil at the separated end and passing toward the other end to cause a complete separation of the 100 stencils, and intermittently operating means for removing the separated stencil while said side separating means support the stencils remaining in said magazine.

5. In an article feeding mechanism, the 105 combination of a magazine for a stack of articles, a pair of rotary disks arranged at opposite sides of the magazine and against which one end of the stack is pressed, said disks having radial recesses and rotating 110 in opposite directions, the portions adjacent to the recesses being adapted to enter into the space between the end article of the stack and the next article to cause the sides of the end article to pass through said recesses to a 115 position beyond said disks for completely separating the end article from the next article of the stack, and a reciprocating device which is arranged beyond said disks in a position to receive the end article and 120 which carries said end article away from said stack.

6. In an article feeding mechanism, the combination of a magazine for a stack of articles, feed means for discharging articles 125 one at a time from said magazine, a reciprocating feed member having a part extending underneath said feed means and upon which the articles are fed by said feed means, said feed member having a slot into 130

which a side of an article is adapted to enter, the upper flange of said slot being omitted in said extending part of the reciprocatory member, whereby movement of 5 said member toward the article causes the article to enter said slot.

7. In an article feeding mechanism, the combination of a magazine for a stack of articles, article-removing means for placing 10 the articles one at a time below said magazine, a reciprocatory member including a plate adapted to pass underneath said article removing means and over the article beneath said means, and hooked portions on 15 said plate adapted to engage said article to feed the same from its position beneath said means.

8. In an article feeding mechanism, the combination of a magazine for a stack of 20 articles, a pair of rotary disks arranged at opposite sides of the magazine and at one end thereof and against which the stack of articles is pressed, said disks having radial recesses, a suction device for separating one 25 end of the end article from an adjacent article, whereby said end article will pass into said recesses of the disks and will be moved to a position beyond said disks, and a finger which is movable into engagement 30 with the article for positively holding said article against endwise movement while operated upon said disks.

9. In an article feeding mechanism, the combination of a magazine for a stack of 35 articles, a pair of rotary disks arranged at opposite sides of the magazine and at the bottom thereof and which constitute the entire support of the stack of articles, said disks having radial recesses, means for causing 40 parts of said articles to enter into said recesses, whereby the rotation of the disks causes the entire end article of the stack to be moved to a position below said disks, and a reciprocatory feed member adapted to 45 receive said article when beyond said disks and to move the same from its position beyond said disks.

10. In a mechanism for feeding articles one at a time from a stack of articles, the 50 combination of a magazine for the stack of articles, means for removing said articles one at a time from said magazine, a reciprocatory feed member adapted to engage one side of said articles for feeding the same 55 forwardly, a stationary guide member relatively to which said articles move, and means on said stationary guide member for preventing said articles from moving rearwardly.

60 11. In an article feeding mechanism, the combination of a magazine for supporting a stack of articles, a pair of rotary disks arranged at one end of said magazine and against which said stack of articles is 65 pressed, radial slots in said disks through

which the end article of the stack is adapted to be passed to a position at the opposite side of said disks, a reciprocatory feed member engaging one edge of an article after the same has passed to the opposite side of 70 said disks, and a stationary guide member cooperating with said feed member for holding said articles in alinement and for preventing rearward movement thereof.

12. In a mechanism for feeding articles 75 one at a time from a stack of articles, the combination of a magazine for the stack of articles, means for removing said articles one at a time from said magazine, a reciprocatory feed member adapted to engage 80 one side of said articles for feeding the same forwardly, said feed member having a slot into which one edge of the article is adapted to enter, a stationary guide member having a corresponding slot into which the opposite side of the article is adapted to enter, and means on said feed member and 85 said guide member for engaging said articles to permit the same to move forwardly and to resist the movement of the 90 articles rearwardly.

13. In a mechanism for feeding articles one at a time from a stack of articles, the combination of a magazine for the stack of 95 articles, means for removing said articles one at a time from said magazine, a reciprocatory feed member adapted to engage one side of said articles for feeding the same forwardly, hooked portions on said reciprocatory member adapted to engage the 100 rear ends of the articles to move the same forwardly and a stationary guide member engaging the opposite sides of the articles and provided with hooked portions adapted 105 to engage the rear ends of said articles to prevent the same from moving rearwardly.

14. In a mechanism for feeding articles one at a time from a stack of articles, the combination of a magazine for the stack of 110 articles, means for separating said articles one at a time from said magazine, a reciprocatory feed member adapted to engage one side of said articles for feeding the same forwardly, a plate on the front end of said reciprocatory member adapted to pass over 115 the separated articles and provided with hooked members adapted to engage the rear ends of said articles to move the same forwardly, other hooked members on said reciprocatory member adapted to engage the 120 articles adjacent to one side thereof, and stationary hooked members adapted to engage the other side of said articles to hold the same against rearward movement.

15. In an article feeding mechanism, the 125 combination of a magazine for a stack of articles, a pair of rotary disks arranged at opposite sides of the magazine and at one end thereof and against which the stack of articles is pressed, said disks having radial 130

recesses through which the lowest article of the stack is adapted to pass to a position beneath said disks, a reciprocatory member including a plate adapted to pass underneath said disks and over the article beneath said disks, and hooked portions on said plate adapted to engage said article to feed the same from its position underneath said disks.

16. In an article feeding mechanism, the combination of a magazine for a stack of articles, a pair of rotary disks arranged at opposite sides of the magazine and at one end thereof and against which the stack of articles is pressed, said disks having radial recesses through which the articles are passed to a position underneath said disks, a reciprocatory feed member having a part extending underneath said disks and upon which the articles are fed by said disks, said feed member having a slot into which a side of an article is adapted to enter, the upper flange of said slot being omitted in said extending part of the reciprocatory member, whereby movement of said member toward the article causes the article to enter said slot.

17. In a mechanism for feeding articles, the combination of a reciprocatory feed member, hooked portions on said feed member which engage the articles to advance the same intermittently, a magazine into which the articles are discharged by said feed member, a cover over said magazine, and hooked members on said cover adapted to engage the article after the same has been moved into a position above said magazine and to hold the article against rearward movement.

18. In a mechanism for feeding articles, the combination of a reciprocatory feed member, hooked portions on said feed member which engage the articles to advance the same intermittently, a magazine into which the articles are discharged by said feed member, a cover over said magazine, means for pivotally supporting said cover to adapt the same to swing into a position clear of said magazine, and means on said cover when in operative position over said magazine adapted to engage articles moved into operative relation to said magazine by said reciprocatory member and to hold said articles against rearward movement.

19. In a mechanism for feeding articles, the combination of a reciprocatory feed member, hooked portions on said feed member which engage the articles to advance the same intermittently, a magazine into which the articles are discharged by said feed member, a cover movably arranged over said magazine, means on said cover for engaging the articles fed to said magazine to hold the same against rearward movement, and means on said cover for holding the

articles delivered to said magazine in alignment with said magazine.

20. In an article feeding mechanism, the combination of a stack of articles, and means which are arranged at opposite sides of said stack and which constitute the sole support for said stack, said supporting means and said stack being relatively movable and said supporting means having slots through which the sides of the lowest article of the stack may pass during the relative movement of said stack and supporting means, and a reciprocating article-receiving member arranged below said supporting means and on which the lowest article is deposited and which carries said article from the stack.

21. In an article feeding mechanism, the combination of a stack of articles, means which are arranged at opposite sides of said stack and which constitute the sole support for said stack, said supporting means and said stack being relatively movable and said supporting means having slots through which the sides of the lowest article of the stack may pass during the relative movement of said stack and supporting means, a reciprocating slide arranged below said supporting means for removing articles after they have been removed from the stack, and means engaging the lowest article for holding the same against endwise movement by said supporting means and said slide.

22. In a mechanism for feeding sheets, the combination of a pair of members having parts supporting the side portions of the sheets and parts engaging said side portions to guide the sheets, one of said members being stationary and the other member being adapted to reciprocate, parts on said reciprocating member which are adapted to engage the end edge of the sheet for advancing the same, and parts on said stationary member for preventing rearward movement of the sheets.

23. In a mechanism for feeding sheets, the combination of a pair of members having parts supporting the side portions of the sheets and parts engaging said side portions to guide the sheets, one of said members being stationary and the other member being adapted to reciprocate, parts on said reciprocating member which are adapted to engage the end edge of the sheet for advancing the same, parts on said stationary member for preventing rearward movement of the sheets, and means for feeding sheets one at a time to said members.

24. In a mechanism for feeding stencils, the combination of a magazine for a stack of stencils, means for removing the stencils one at a time from said magazine, an intermittent stencil-advancing mechanism including a pair of guide members having

slots in the sides thereof into which the edge portions of said stencils extend, stencil engaging means on said guide members, and means for placing the edge portions of the 5 stencils removed from said magazine into said guide members.

25. In a mechanism for feeding sheets, the combination of a magazine for a stack of sheets, means for feeding the sheets one at 10 a time from said stack to a position below said stack, and sheet-advancing mechanism including a reciprocatory member adapted to pass between said sheet and said stack and to engage the rear end of said sheet to 15 advance the same, and guide means engaging the side edges of the sheets to hold the same substantially flat.

26. In a mechanism for feeding sheets of flexible material, the combination of a magazine for a stack of sheets, a substantially flat 20 table below said magazine to which the sheets are fed singly, a pair of guide members

bers having slots adapted to receive the opposite side edge portions of said sheets to hold said sheets substantially flat, so that the opposite faces of the middle portions of said sheets are accessible, and means for feeding said sheets from said table to said guide members.

27. In a mechanism for feeding sheets of 30 flexible material, the combination of a magazine for a stack of sheets, a substantially flat table below said magazine to which the sheets are fed singly, a pair of guide members 35 having slots adapted to receive the opposite side edge portions of said sheets to hold said sheets substantially flat, so that the opposite faces of the middle portions of said sheets are accessible, a sheet engaging hook on one of said guide members, and means 40 for reciprocating said guide member to advance the sheets.

WILLIAM E. PEDRICK.

•

Certificate of Correction.

It is hereby certified that in Letters Patent No. 1,448,314, granted March 13, 1923, upon the application of William E. Pedrick, of Buffalo, New York, for an improvement in "Mechanism for Feeding Stencils or Analogous Articles," errors appear in the printed specification requiring correction as follows: Page 5, line 16, for "Fig. 2" read *Fig. 22*; page 6, line 95, claim 4, for the word "and" read *an*; page 7, line 32, claim 8, after the word "upon" insert the word *by*; and that the said Letters Patent should be read with these corrections therein that the same may conform to the record of the case in the Patent Office.

Signed and sealed this 17th day of April, A. D., 1923.

[SEAL.]

KARL FENNING,
Acting Commissioner of Patents.
